UNITED STATES PATENT OFFICE.

WILLIAM C. CARTER, OF ST. LOUIS, MISSOURI, ASSIGNOR TO CARTER CARBURETOR COMPANY, OF ST. LOUIS, MISSOURI, A CORPORATION OF MISSOURI.

CARBURETER.

1,184,923.

Specification of Letters Patent. Patented May 30, 1916.

Application filed April 24, 1911. Serial No. 623,016.

To all whom it may concern:

Be it known that I, WILLIAM C. CARTER, a citizen of the United States, residing at St. Louis, Missouri, have invented a certain new and useful Improvement in Carbureters, of which the following is a full, clear, and exact description, such as will enable others skilled in the art to which it appertains to make and use the same.

19 This invention relates to carbureters, and particularly to carbureters of the type in which the supply of liquid fuel is regulated by means of a mechanically-operated needle valve that is controlled by the mechanism 15 which operates the throttle valve of the motor.

One object of my invention is to provide a carbureter of the type referred to which is economical in the consumption of fuel.

23 Another object is to provide a carbureter which will produce a proper mixture at high, low or intermediate speeds of the motor on which it is used.

Another object is to provide a carbureter 25 which is so designed that sufficient suction is provided adjacent the fuel jet when the motor is throttled down to cause a charge of the proper richness to enter the cylinders of the motor. And still another object is 30 to provide a carbureter that comprises means for introducing fuel laterally into the main air passageway of the carbureter at a point above the main fuel supplying device when the motor is throttled down, in such a manner that said fuel travels upwardly through 35 the intake of the motor with a whirling action, thus insuring a uniform supply to all cylinders of the motor.

Other objects and desirable features of 40 my invention will be hereinafter pointed out.

Figure 1 of the drawings is a front elevational view of a carbureter constructed in accordance with my invention; Fig. 2 is 45 a vertical sectional view of Fig. 1; Fig. 2^a is a perspective view of the track which forms part of the mechanism for actuating the jet valve; Fig. 3 is a top plan view of the carbureter; Fig. 4 is a side elevational 50 view; Fig. 5 is a vertical cross sectional view taken on approximately the line 5—5 of Fig. 1, looking in the direction indicated by the arrow; Fig. 6 is a vertical cross sectional view taken on the line 6—6 of Fig. 1, looking 55 in the direction indicated by the arrow;

and Fig. 7 is a detail view illustrating a slight modification of the actuating mechanism for the jet valve.

Referring to the drawings which illustrate the preferred form of my invention, A designates a substantially tubular-shaped member provided at its upper end with a flange 1 that is adapted to be connected to the intake pipe of the motor so as to form a passageway through which air is drawn by the suction created in the cylinders of the motor. The lower end of the member A branches laterally, as shown in Figs. 1 and 2, and said member is provided intermediate its ends with an annular-shaped flange 2 so as to produce a contracted portion 3 intermediate the ends of the air passageway and thus increase the suction at this point. A vertically disposed fuel supply tube 4 is arranged in the lower portion of the member A, as shown in Fig. 2, and said tube is provided with a fuel jet or orifice 5 that is located adjacent the contracted air passageway 3 inside of the member A, the upper end of said tube 4 being closed by a cap 6 and the lower end of said tube communicating with a fuel duct 7 that leads to a float chamber B. An open-ended sleeve 8 surrounds the upper portion of the fuel supply tube 4 and the interior of said sleeve 85 communicates with a duct or pipe 9 which extends upwardly and leads into the main air passageway of the carbureter at a point above the place where the main fuel supply device 5 discharges into said passageway so as to introduce fuel laterally into the upper portion of said passageway when the motor is throttled down.

In the form of my invention herein shown the upper end of the duct 9 terminates above the throttle valve and thus forms a by-pass around the throttle valve, but I wish it to be understood that my invention is not limited to such a structure, for my broad idea consists in a carbureter provided with 100 means whereby when the motor is throttled down fuel will be introduced laterally into the main air passageway of the carbureter at a point above the place where the main fuel supplying device is located and in such 105 a manner that a uniform supply of fuel is insured for all cylinders of the motor, as hereinafter described.

The sleeve 8 is enough larger than the fuel supply pipe 4 to form a passageway 110

between said pipe and the interior of the sleeve through which the air can travel when the throttle valve is open. The upper end 9^a of the vaporized fuel duct or by-pass 9 is arranged tangential with reference to the tubular-shaped passageway with which the upper end of said duct communicates and it also inclines upwardly, as shown in Figs. 3 and 6, so as to impart a circular motion or upward whirling action to the charge of vaporized fuel which emerges from said duct when the motor is throttled down. By forming the upper end of the duct 9 in this manner I overcome the possibility of some of the cylinders of the motor receiving an exceedingly rich charge and the other cylinders receiving a charge which is deficient in fuel for the whirling action above referred to causes the fuel and air to be thoroughly mixed and to be introduced into the intake pipe of the motor in such a manner that there is no tendency for the air to take one path and enter some of the cylinders and the fuel to take a different path and enter the other cylinders of the motor.

In the embodiment of my invention herein shown, the vaporized fuel duct 9 is formed by a pipe which is embedded in the wall of 30 the member A during the process of casting said member, and the sleeve 8 which surrounds the fuel jet is connected to the lower end of said pipe, as shown in Fig. 2. I do not wish it to be understood, however, that 35 my invention is limited to the exact construction herein shown for the carburetor could be constructed in various other ways and still accomplish the same results without departing from the spirit of my invention.

A needle valve 11 is provided for regulating the flow of the liquid fuel through the orifice or jet 5 in the fuel supply pipe 4, said needle valve being arranged at approximately right angles to the open-ended 45 sleeve 8 and projecting through an opening in said sleeve, as shown in Fig. 5, so that its pointed end will enter the fuel jet 5 and thus increase or diminish the flow of fuel 50 from said jet according to the position of the needle valve. The mechanism for actuating the needle valve 11 is of novel construction and consists principally of an adjustable track C which moves when 55 the throttle valve 10 is operated, and a lever 12 pivotally mounted intermediate its ends on a bracket 13 on the member A, and arranged with its upper end in engagement with the track C and 60 its lower end in alignment with a spring-pressed plunger 14 which carries the needle valve 11. As shown in Fig. 5, the needle-valve-carrier 14 is reciprocatingly mounted in the member A and it is provided at its 65 outer end with a flange 14^a which is acted

upon by a coiled expansion spring 15 that tends to force the carrier 14 outwardly so as to exert sufficient pressure on the lower end of the lever 12 to hold the upper end of said lever in engagement with the track C, the spring 15 being arranged on the carrier 14 between the member A and the flange 14^a on the outer end of said carrier. The needle 11 is retained in the carrier 14 by means of a bushing 16 at the inner end of 70 the carrier which acts as a stop for the head on the outer end of the needle valve, and a coiled expansion spring 17 is arranged in a pocket in the carrier 14 so as to form a cushion or yielding abutment for the needle valve which permits said valve to yield or move relatively to the carrier 14 in case the carrier is forced inwardly too far, thereby eliminating the possibility of the needle valve being forced too far into the fuel 85 jet 5.

In order that the needle valve may be adjusted accurately with reference to the lever 12 which operates it so as to obtain the proper supply of fuel at low speed of the 90 motor, I have provided said lever with an adjustable member 18 which bears against the outer end of the needle-valve-carrier 14, said member having a substantially cup-shaped head which receives the outer end 95 of the needle-valve-carrier, as shown in Fig. 5, and a screw-threaded shank 19 which passes through a screw-threaded opening in the lower end of the lever 12. By turning the member 18 in one direction or the other 100 the needle-valve-carrier can be moved inwardly or outwardly and thus change the position of the needle with reference to the fuel jet 5. Any suitable means may be employed for locking the member 18 in position, the means herein shown consisting of a spring-pressed ball 20 mounted in an arm 105 on the lever 12 which engages teeth or serrations in the outer surface of the member 18, as shown in Fig. 4.

The track C is substantially arc-shaped, as shown in Figs. 1 and 2^a, and its front face, against which the upper end of the lever 12 bears, is tapered longitudinally and also transversely, thus forming an approximately arc-shaped wedge which is also wedge-shaped in cross section, as shown in Figs. 2^a and 6. Said track is carried by an arm or pin 21 that projects downwardly 115 from the rock shaft 22 to which the throttle 120 valve 10 is connected, and it is mounted on said pin in such a manner that the upper reduced end of the track can be adjusted inwardly and outwardly so as to vary the throw of the lever 12, the pin 21 being round 125 in cross section and passing loosely through a hole that is formed in the lower end portion of the track. The means herein shown for adjusting the track C laterally or turning it about the pin 21 as an axis, consists 130

of a screw 23 adjustably mounted in an arm 24 on the throttle valve shaft 22, and provided at its inner end with a spool-shaped head 25 into which the upper end of the 5 track C projects, as shown clearly in Fig. 6. By turning the screw 23 in one direction the upper end of the track C will be moved outwardly and thus increase the throw of the lever 12, and by moving said screw 23 10 in the opposite direction the upper end of the track C will be moved inwardly, thereby reducing the throw of the lever 12. I have herein shown the screw 23 provided with a spring-pressed ball 26 that coöperates 15 with teeth or serrations on the arm 24 in which said screw is mounted so as to lock the screw in adjusted position, but it will, of course, be understood that various other means could be used for this purpose 20 without departing from the spirit of my invention. The screw 23 is used for changing the position of the track C so as to adjust the needle valve 11 in the proper position to obtain the required quantity of fuel 25 on high speed of the motor, namely, when the throttle valve is wide open, but a separate and distinct means is employed for obtaining the proper adjustment of the needle valve 11 at intermediate speed or when the 30 motor is partially throttled down. This latter adjustment may be effected either by shifting the track C vertically relatively to the lever 12 so as to cause the upper end of the lever 12 to travel on the high or low 35 part of the front face of the track C or by shifting the lever 12 vertically relatively to the track C to accomplish the same result.

In Fig. 1 I have shown the track C as being provided at its lower end with a depending lug C' through which a cotter key 27 on the pin 21 passes, said pin being provided with a number of openings for receiving said cotter key so as to enable the track C to be adjusted vertically on the pin 21, and 45 in Fig. 7 I have shown a slightly different construction wherein the lever 12 is provided with a vertically adjustable extension 12^a that coöperates with the track C, said extension having a number of openings which 50 receive a cotter key 27^a on the lever 12. The front face of the track C is not formed on a straight taper from the lower to the upper end of said track but the intermediate portion of said front face is hollowed out or 55 curved slightly, as shown in Fig. 2^a, so as to permit the upper end of the lever 12 to move inwardly a trifle farther at intermediate speed than at high speed of the motor for a purpose hereinafter described.

60 When the throttle valve is closed, as shown in Fig. 2, the track C will occupy the position shown in Fig. 5 so that very little fuel can escape through the fuel jet 5. When the throttle valve is opened the track C 65 moves to the right of Fig. 1, thus permitting

the upper end of the lever 12 to move inwardly and consequently moving the needle valve 11 outwardly or into such a position that more fuel can escape from the fuel jet 5. If the supply of fuel which escapes from 70 the fuel jet 5 is not sufficient when the throttle valve is wide open, the operator adjusts the screw 23 so as to move the upper end of the track C inwardly, and if the supply of fuel is too great the operator adjusts 75 said screw 23 so as to move the upper end of the track C outwardly. If the supply of fuel which emerges from the fuel jet 5 is not sufficient when the motor is partially throttled down to intermediate speed the operator 80 adjusts the track C downwardly on the pin 21 so as to permit the upper end of the lever 12 to move inwardly farther when the track C has been shifted partway to the right from the position shown in Fig. 1, and 85 if the supply of fuel is too great when the motor is partially throttled down the operator adjusts the track C upwardly so as to move the needle valve 11 inwardly a trifle farther when the track is in its intermediate position. The adjustment of the fuel for low speed or when the motor is throttled way down is effected by turning the member 18 which coöperates with the 90 needle valve carrier 14. As previously 95 stated, the central portion of the track C is curved or hollowed-out slightly so as to cause the needle valve to be drawn outwardly farther at intermediate speed than at high speed when the throttle valve is wide open. If the needle valve moved proportionately the same distance as the throttle valve when the throttle valve moved from its closed to its partly opened position, the suction in the upper part of the air passage-way would not be sufficient to draw the proper quantity of fuel out of the fuel jet 5 to produce a proper mixture. Therefore, 100 I have formed the track C in such a manner that the orifice through which the fuel escapes is larger when the throttle valve is only partly open than it is when the throttle valve is wide open, the increase in the dimensions of the fuel orifice compensating 105 for the relatively small suction and thus insuring a sufficient supply of fuel at intermediate speed to produce a charge of the proper richness.

A carbureter of the construction above described is economical in the consumption of fuel and produces a combustible gas of the proper richness at all speeds of the motor; and another very desirable feature of my carbureter is that sufficient suction is provided adjacent the fuel orifice 5 when the 110 motor is throttled down to insure a steady flow of fuel from said orifice and to insure the mixing of said fuel with a proper quantity of air to produce a combustible mixture. This, of course, is due to the fact 115 120 125 130

that the duct 9 which terminates in the main air passageway adjacent the throttle valve has its lower end communicating with the open-ended sleeve 8 in the air passageway which surrounds the fuel jet 5. Said duct and sleeve establish practically a direct communication between the fuel jet and the intake pipe of the motor when the motor is throttled down and as said sleeve is always in direct communication with the atmosphere the air which enters same will vaporize the fuel which is sucked up through the duct 9 into the cylinders.

In addition to the desirable features above-mentioned, such a structure prevents the fuel from splashing out of the fuel jet and being wasted when the motor is throttled down and when the machine is traveling over a rough road because the suction that is created adjacent the fuel jet is so strong that the fuel is drawn directly from said jet up through the duct 9 through which air is traveling. When the throttle valve is opened the air, of course, will travel through the contracted passageway 3 in the tubular member A and thus suck the fuel out of the fuel jet and vaporize it while it is traveling through the passageway which the throttle valve 10 controls.

The lower end of the air passageway in the tubular-shaped member A is normally open but when the motor is cranked or started said passageway is closed or choked by a valve 28 arranged in the laterally projecting portion of the member A, as shown in Fig. 2, said valve being connected to a shaft 29 which is provided at its outer end with an arm 30 to which an operating device, not shown, is connected, a coiled spring 31 or other suitable device being provided for normally holding the valve in its wide-open position shown in Fig. 2. A small recess or depression 32 is formed in the bottom of the member A directly under the shaft of the valve 28 so that when said valve is closed a small opening will be provided at the edge of the valve through which air can travel. When the valve 28 is closed and the motor is cranked the suction produced in the member A is sufficient to cause the fuel to flow out of the fuel jet 5 and fall downwardly onto the bottom of the member A where it collects in the recess or depression 32, thus forming a small puddle of fuel which is vaporized and converted into a starting charge by the air which travels under the edge of the valve 29. After the motor has been started the valve 28 is released so that it can move into its wide-open position shown in Fig. 2.

I have not herein described the construction of the mechanism in the float chamber B that operates the valve 33 which controls the supply of liquid fuel to said float chamber as said mechanism forms the subject-

matter of my pending application Serial No. 623,017, filed April 24, 1911.

Having thus described my invention, what I claim as new and desire to secure by Letters Patent is:

1. A carbureter provided with an air passageway through which the air is drawn by the suction produced by the engine on which the carbureter is used, a throttle-valve, a duct of the same cross sectional area throughout its entire length that forms a by-pass around said throttle-valve, said duct being separate and distinct from the throttle-valve and always remaining wide open irrespective of the position of the throttle-valve, a hollow member in said passageway communicating with the lower end of said duct and having its upper end open and presented toward the throttle, and a variable means for supplying fuel to said member. 75

2. A carbureter provided with an air passageway through which the air is drawn by the suction produced by the engine on which the carbureter is used, a throttle-valve, a duct that forms a by-pass around said throttle-valve, a hollow member in said passageway communicating with the lower end of said duct and having its upper end open and presented toward the throttle, means for supplying fuel to said member, and a manually-controlled valve arranged adjacent the lower end of said passageway for cutting down the flow of air into said passageway when the motor is started. 85

3. A carbureter provided with an air passageway through which the air is drawn by the suction produced by the engine on which the carbureter is used, a fuel jet or supplying device arranged in said passageway, a throttle valve arranged between said fuel jet and the means which induces a circulation of air through said passageway, an open-ended sleeve surrounding said fuel jet and spaced away from the walls of said air passageway so as to permit the air to travel through said space, and a by-pass around said throttle valve formed by a duct which communicates at one end with the interior of said sleeve and having its other end terminating above the throttle valve. 100

4. A carbureter having an air passageway provided intermediate its ends with a contracted portion, a fuel jet arranged inside of said passageway adjacent said contracted portion, a throttle valve arranged between said fuel jet and the cylinder of the motor on which the carbureter is used, an open-ended sleeve surrounding said fuel jet and arranged in the contracted portion of said air passageway, and means for establishing direct communication between the interior of said sleeve and the cylinder of the motor at all times, both when the throttle valve is closed and open. 110

5. A carbureter having an air passage- 125

way which communicates at one end with the atmosphere and at the other end with the cylinder of the motor on which the carbureter is used, said passageway having a contracted portion, a fuel jet arranged in the contracted portion of said passageway, a throttle valve arranged between said fuel jet and the cylinder of the motor, a duct that is open at all times and which leads from a point between said throttle valve and the cylinder of the motor and terminates adjacent said fuel jet, and means coöperating with said duct and surrounding the fuel jet for creating a strong suction adjacent said fuel jet when the throttle valve is closed.

6. A carbureter provided with an air passageway which is normally wide open and in communication at one end with the atmosphere, a throttle valve arranged adjacent the opposite end of said passage, a vertically disposed fuel supply tube arranged in said passageway and having its upper end closed, a fuel jet in the side of said tube through which the fuel can escape laterally, an open-ended sleeve surrounding the portion of said tube in which said fuel jet is formed, and a duct leading from the interior of said sleeve and terminating above the throttle valve.

7. A carbureter provided with an air passageway that communicates with the intake pipe of a motor, a fuel supplying device arranged in said passageway and provided at one side with a jet or orifice through which the fuel escapes, a needle valve for regulating the flow of the fuel, a throttle valve arranged between said jet and the intake pipe of the motor, a duct having one end terminating in close proximity to said fuel jet and its other end terminating on the opposite side of the throttle valve, and means controlled by the throttle valve for changing the position of said needle valve so as to vary the flow of fuel from said jet as the speed of the motor varies.

8. A carbureter having an air passageway provided intermediate its ends with a contracted portion, a fuel jet or supplying device arranged in said passageway adjacent said contracted portion, a throttle valve arranged between said fuel jet and the suction-producing means of the engine on which the carbureter is used, a duct leading from a point between said throttle valve and suction-producing means and terminating in such close proximity to said fuel jet that the fuel will be sucked out of said jet and up through said duct when the throttle valve is closed, means arranged at the lower end of said duct for confining the suction in said duct to the jet, a mechani-

cally-operated needle valve which varies the flow of fuel from said jet as the suction of the motor varies.

9. A carbureter having an air passageway provided intermediate its ends with a contracted portion, a fuel jet arranged inside of said passageway adjacent said contracted portion, a throttle valve arranged between said fuel jet and the cylinder of the motor on which the carbureter is used, an open-ended sleeve surrounding said fuel jet and arranged in the contracted portion of said air passageway, a duct communicating with the interior of said sleeve and having its other end terminating between said throttle valve and the cylinder of the motor, a needle valve coöperating with said jet, and means for changing the position of said needle valve when the position of the throttle valve is changed so as to vary the supply of fuel.

10. A carbureter having an air passageway, a needle valve for controlling the supply of liquid fuel to said passageway, a throttle valve arranged between said needle valve and the intake pipe of the motor, means for automatically changing the position of said needle valve as the position of the throttle valve is changed so as to vary the supply of liquid fuel to said air passageway, and an unobstructed duct or open passageway that forms a by-pass around the throttle valve and thus establishes communication between said air passageway and the intake pipe of the motor at all times both when the motor is throttled down and running at high speed.

11. A carbureter having an air passageway that is normally wide-open when the motor is in operation, means for choking or partially closing said passageway when the motor is first started, a fuel-supplying jet in said air passageway, a throttle valve arranged in said air passageway, a mechanically-operated needle valve operatively connected to the throttle valve for controlling the supply of liquid fuel from said jet into said air passageway, a by-pass around said throttle valve which permits vaporized fuel to flow into the intake pipe of the motor when the motor is throttled down, and a device arranged adjacent said fuel jet and coöperating with said by-pass to produce an intense suction at the fuel-supplying jet.

In testimony whereof I hereunto affix my signature in the presence of two witnesses, this twentieth day of April 1911.

WILLIAM C. CARTER.
